UNITED STATES PATENT OFFICE.

JOHN HENRY MORRISON, OF SALIDA, COLORADO; GEORGIA A. MORRISON
EXECUTRIX OF SAID JOHN HENRY MORRISON, DECEASED.

SURGICAL PAD.

SPECIFICATION forming part of Letters Patent No. 542,202, dated July 2, 1895.

Application filed May 7, 1894. Serial No. 510,332. (No model.)

To all whom it may concern:

Be it known that I, JOHN HENRY MORRISON, of Salida, in the county of Chaffee, in the State of Colorado, have invented new and useful Improvements in Surgical Pads, of which the following, taken in connection with the accompanying drawings, is a full, clear, and exact description.

My invention consists of a surgical pad; and it has for its object the production of a simple and practical device, which is easily carried, thoroughly cleaned, and quickly arranged in operative condition, is particularly applicable for use upon an operating table or chair in surgical and obstetrical work, prevents escape of liquids, &c., from the rear and side edges of the pad and conducts the same to a suitable vessel or receptacle; and to this end it consists, essentially, in a substantially rectangular pad provided with an inflatable cushion of substantially U shape surrounding three sides or edges thereof and having its intermediate portion arranged at the rear edge of the pad and its extremities arranged at the side edges thereof.

It also consists in a pad provided with a drain-conduit detachably secured thereto and having an outlet-opening in its free end and an inlet-opening in its opposite end for receiving the liquids, &c., discharged from the adjacent portion of the pad, and in the detail construction and arrangement of its component parts.

In describing this invention reference is had to the accompanying drawings, forming a part of this specification, in which like letters indicate corresponding parts in all the views.

Figure 1 is an isometric view of my improved pad shown in operative position. Figs. 2 and 3 are respectively longitudinal, vertical, and transverse horizontal sectional views taken on lines 2 2 and 3 3, Fig. 1.

In my previous patent, No. 489,132, dated January 3, 1893, I have set forth a surgical apron applicable for use upon beds in surgical and obstetrical work and formed with an inflatable cushion at its rear end and thickened or raised front and side edges. This

apron is necessarily of sufficient width to render its use impractical upon operating tables and chairs, usually of much less width, and even though constructed of suitable size the thickened or raised side and front edges are more or less ineffective in preventing the escape of liquids, &c., when the apron is placed upon a substantially flat and rigid surface instead of one depressed and yielding, as that portion of the bed supporting a patient. It is also more or less impractical and expensive to form these front and side edges of considerable thickness, and the apron is unprovided with means for conducting from its upper face the liquids, &c., discharged thereupon. Such an operation is essential in a surgical device of this character intended for use upon operating tables or chairs, for which my present invention is particularly designed.

Heretofore it has been common to surround a flat sheet with raised edges formed of inflated cushions, and the latter have been made tapering from front to rear, so as to give such an inclination to the pad as would cause all liquids received therein to flow to the rear and out through a suitable drain-pipe, which was of comparatively stiff and unyielding rubber, so that it could not be compressed by the weight of the patient; but in the present instance I make the cushion of substantially U shape extending along the rear edge and the two opposite sides of the pad, and slightly larger or thicker at the rear, so as to give the pad an inclination toward the front, and the absence of any raised edges or cushion at the front leaves an open space here out which the liquids can freely pass into a conduit detachably connected therewith, all as will be clear from the following specific description.

In the drawings the letter A represents a flat sheet of flexible material approximately rectangular in plan and forming the bottom of the pad, which latter is provided with an inflatable cushion B and a drain-conduit C, and is preferably composed of rubber or other impervious material. The cushion B, which is formed of similar material, is of U shape and so disposed that its intermediate portion b is arranged at the rear edge a of the pad

A and its extremities $b' b'$, along the opposite sides $a' a^2$, extending from the opposite ends of the edge a .

An air-valve suitably secured to the cushion 5 B permits the entrance and escape of air, and said cushion B, when inflated, forms a raised surface at the rear and opposite sides of the pad A, and obviously serves to prevent the escape therefrom of liquids, &c., 10 discharged upon the pad, and also acts as a cushion for yieldingly supporting the adjacent portion of the body of the person operated upon. It is evident, however, that a raised rib may be used instead of the inflatable cushion B, but such is not the preferable construction, as the pad would not be as easily carried or cleaned, and its cost of manufacture would be considerably increased.

As clearly seen at Figs. 1 and 4, the ends 15 $b^2 b^2$ of the opposite extremities $b' b'$ of the cushion B are contracted or formed of gradually decreasing cross-sectional area and are inclined toward each other, and the front edge of the pad A is provided with a flap or 20 projecting portion a^3 , extending beyond said ends $b^2 b^2$ and formed at its base with perforations $a^4 a^4$. The drain-conduit C, which is preferably removably secured to the remaining portion of the pad, is of suitable construction and is provided with a flaring upper end c , formed with an inlet opening c' , of 25 sufficient width to receive the flap or projecting portion a^3 . The free or opposite end of the conduit C is formed with an outlet 30 opening c^2 , and is aligned with a suitable vessel or receptacle preferably resting on the floor, and into which the liquids and materials conducted through the drain-conduit C are discharged.

40 In the practical operation of my pad the drain-conduit C is arranged normally at right angles with the remaining portion of the pad, and its rear wall c^3 is provided with perforations c^4 , aligned with the perforation

45 a^4 of the flap or projecting portion a^3 of the pad A. A fastening-piece D is arranged at the outside of the wall c^3 and is provided with projections $d d$, passed through the perforations $c^4 a^4$ and having heads or shoul-

50 ders d' at their free ends for engaging the front face of the flap or projecting portion a^3 . When not in use, or when it is desired to clean the pad, the conduit C is detached from the flap or projecting portion a^3 . The fasten-

55 ing-piece D is detached from the wall c^3 of the conduit, and the parts are then thoroughly cleaned. This is a particularly simple form of fastening means for securing the outlet-conduit in operative position and permitting 60 of its ready disengagement; but it is evident that other suitable fastening means may be used, if desired, and that the fastening projections may be secured to the drain-conduit. It is sometimes desirable to distend the inlet-

65 opening c' of the conduit C to its utmost limit, and said conduit is therefore provided

with separated loops C', projecting from the inner face of its front wall, and the opposite ends of an outwardly-curved stiffening-bar C², formed of suitable material, is passed 70 through said loops.

The peculiar construction of the cushion B greatly facilitates cleaning of my improved pad and reduces its cost of manufacture.

The cushion B is formed of material 75 integral with the pad A, and its opposite sides, as clearly seen at Fig. 2, are of substantially the same width, and when inflated the opposite faces of the cushion project equally above and below the plane of the pad. Consequently when the cushion is deflated it increases in width without any liability of the production of gathers or wrinkles therein, and its thorough cleaning is thereby greatly facilitated. Moreover, there is no chance for matter 85 to accumulate between the cushion and the pad A, as there is no space between said parts in which material can accumulate.

The operation of my invention will be readily understood upon reference to the accompanying drawings and the foregoing description, and it will be particularly noted that it is applicable for use upon operating tables or chairs in surgical and obstetrical work, prevents the escape of liquids, &c., from the rear 90 side edges of the pad and conducts the same and practically and effectively to a suitable vessel or other receptacle, is easily and thoroughly cleaned by deflating the inflatable cushion, detaching the drain-conduit and the fastening-piece and subjecting the parts to the action of a suitable cleaning fluid, is easily and conveniently carried, if desired, and quickly restored to operative position with a minimum amount of labor and attention by 95 inflating said cushion and attaching the drain-conduit in its designed position. The pad may, however, be used without the drain-conduit when desired, and, as it is evident that considerable change may be made in the 100 exact detail, construction, and arrangement of the parts, I do not herein specifically limit myself to such exact detail, construction, and arrangement.

Having thus fully described my invention, 115 what I claim as new, and desire to secure by Letters Patent, is—

1. In a surgical pad, the combination with the pad proper surrounded on three sides by a cushion leaving the opposite side open; of 120 a pendent conduit detachably connected with the pad under its open edge, upright separated loops near the inlet end of the conduit, and a transverse stiffening bar detachably engaging said loops, as and for the purpose set 125 forth.

2. In a surgical pad, the combination with a flat sheet forming a pad having a flap at one edge, and an inflated cushion surrounding the three remaining edges and thicker at 130 that edge remote from the flap; of a pendent discharge conduit whose inlet end receives

said flap, the latter and the adjacent wall of the conduit having aligned openings, and a fastening piece provided with headed projections removably passed through said openings, as and for the purpose set forth.

3. A surgical pad consisting of a single piece of flexible material such as rubber and comprising a substantially rectangular flat sheet or pad having a tapering extension or flap at one edge, and a substantially U-shaped inflatable cushion whose central portion extends along the opposite edge and whose extremities extend along the two sides of said pad and terminate short of said flap, the body of

the pad standing opposite the diametric center of the cushion when inflated and said cushion being then thicker at the edge remote from the flap, substantially as described.

In testimony whereof I have hereunto signed my name, in the presence of two attesting witnesses, at Salida, in the county of Chaffee, in the State of Colorado, this 27th day of April, 1894.

JOHN HENRY MORRISON.
